UNITED STATES PATENT OFFICE.

JOSEPH F. MAUER AND GEORGE W. BEISER, OF PERU, ILLINOIS.

DROP STEP FOR PASSENGER COACHES.

Application filed April 10, 1922. Serial No. 551,362.

To all whom it may concern:

Be it known that we, JOSEPH F. MAUER and GEORGE W. BEISER, both citizens of the United States, residing at Peru, in the 5 county of La Salle and State of Illinois, have invented new and useful Improvements in Drop Steps for Passenger Coaches; and we do hereby declare that the following is a full, clear, and exact description 10 of the invention, which will enable others skilled in the art to which it appertains to make and use the same.

This invention relates to a drop-step designed particularly for railway coaches, 15 street cars and the like.

The invention has for its object the provision of an additional step as an attachment for the usual series of steps of a car or coach whereby a safe means of stepping 20 upon or from the depot platform or street is afforded. This is provided as a safety measure, and in order, also, that the passenger may easily mount and dismount without the exertion usually necessary 25 where, on street cars for example, the permanent or fixed step is some considerable distance above the street level.

Also, that on railway coaches when the distance between the steps and the depot 30 platform is considerable the unstable stepping stool usually provided can be discarded and thus eliminate chances of accidents by overturning of the said stepping stool.

While we are aware that it is not entirely new to provide a folding step for the purpose named, certain new structures having advantages in use are included in our invention.

In the appended drawings,

Figure 1 is a side elevation of the pending step arrangement of a railway coach showing our invention attached thereto.

Figure 2 is a similar view, enlarged, showing the two different positions of the mechanism involved in our invention.

Figure 3 shows the invention applied to the step arrangement as seen from the side 50 opposite that illustrated in the earlier figures.

Figure 4 is an elevation of a latch arrangement shown in Figures 1 and 2, and

Figure 5 is an elevation, enlarged, of a 55 latch and trigger release mechanism, also shown in said Figures 1 and 2.

A railway coach and its usual step structure are indicated at 1 and 2, respectively, and the depot platform is denoted at 3 in Figure 1.

Usually the lowest step of a railway coach is about twenty inches above the level of the depot platform and this requires the use of a stepping stool of a height of about half this distance in order to conveniently 60 mount the steps. It is our purpose to provide a step carried on the car or coach that may be let down into position, for replacing the stool, and that will be positively held in the folded position or in position 65 for use.

This step is indicated at 4. Rigidly attached to each of its ends is an arm 5 pivotally supported between the ends of links 6 whose other ends are in turn pivoted to 70 supporting brackets 7 secured to the lowermost portion of the step structure 2 at its forward edge. As indicated in Figure 2, and particularly in Figure 3, the step 4 and its arms 5 are designed to fold into 75 one plane against the underside of the lowermost step of the structure 2, the said step 4 lying between the projections of the supporting brackets 7 when thus stationed. The free ends of the arms extend upwardly 80 and each is pivotally attached to one end of a lever 8 secured upon opposite ends of a horizontal shaft 9 extending through the step structure 2 and preferably having 85 bearings in members secured to each side 90 of the latter. One of these members is designated at 10 at one side of said structure 2 and forms an extension of a casting 11, whose construction and purpose will presently appear. At the other side of the 95 structure, Figure 3, the member 10 is merely a plate secured upon the latter.

The said levers 8 are mounted between their ends as shown, and one end of one of them, at its end opposite that having 100 the arm 5, has pivoted thereto a lock-arm 12. When the step 4 is in use this arm lies within a keeper 12', Figures 2 and 4, while in the folded position of the step said arm takes the vertical position shown in broken 105 lines in said Figure 2, being held by a member 13 in any suitable manner.

The casting 11 referred to includes an arm 14 constituting a stop which lies in a position to receive against it the pivoted 110 ends of the arm 5 and lever 8. In addition, it constitutes a support for a trigger 15.

slidably thereon within guides 16. Said trigger includes a projecting pin 17 engaged by a spring 18 fixed on the stop 14, for example. The spring tends to constantly hold the trigger in a raised position or that shown in Figure 5. 19 is an extension on the casting 11, below the trigger, adapted to form a keeper for a spring 20 secured upon one of the links 6.

0 When the step 4 is in use the parts take the position shown in full lines in Figure 2, the stop 14 firmly securing the said step in the horizontal position without danger of movement due to the weight of a person 15 stepping thereon.

The arm 12 is notched at 12² engaging the keeper 12' upon which it rests. The latter has a peculiar construction in that, as shown in Figure 4, the opening 21 through which 20 the arm extends has a spring 22 therein and an abutment 23 so disposed that when the arm is drawn down between the spring and said abutment the spring will be compressed and when said arm has passed below the abutment said spring will force it beneath the latter, the said notch 12² receiving the keeper into it, preventing the arm having endwise movement while thus positioned. In this manner an additional automatic lock is provided for maintaining the step rigid while in use, preventing its being raised by accident "breaking" the lock constituted by the arm 5, lever 8 and the stop 14. If the step were lifted inadvertently from its position for 30 use to the extent that said lock were broken, the imposed weight of one stepping thereon would tend to swing the step inward, out of position for use, with a possible accident.

When the step is to be raised and folded 40 the arm 12 is moved against the spring 22 and raised above the abutment whereupon it is pulled outward through the keeper drawing with it the arm of the lever 8 to which it is attached, raising the step to the 45 folded position. As this occurs the spring 20 engages the extension 19 of the casting 11, Figure 5, sustaining the step in position. In addition to this, however, we provide additional means for holding the step in position as shown in Figure 3. The free end of 50 the lever 8 at this side of the structure 2 receives upon it a latch 24 pivoted at a point just above the said free end. This forms a positive stop and sustains the step in raised 55 position in addition to the automatic lock provided by the said spring 20. In releasing the step the latch is swung upwardly on its pivot and frictionally engages a spring at 25 from which it is easily disengaged on occasion.

It is noted that the end of the lever 8 to which the arm 12 is pivoted is drawn through the keeper 12' and that therefore the said arm can be raised to the vertical position 65 shown. When dropping the step the arm is

drawn out of the member 13 and swung down upon the top of the trigger 15 which is thus forced upon the spring 20 disengaging that member from the extension 19 permitting the step to drop and in that movement the arm 12 is drawn through the keeper 12' to the position described and shown.

The positive securing of the step in either position, and in an automatical manner as 75 well, is important herein and is fully accomplished by the means employed or the equivalent thereof, we having shown a preferred form thereof.

We claim:

1. In a device of the nature described, the combination with a step structure including an auxiliary step suspended therefrom adapted to fold beneath it, an arm rigidly secured to said auxiliary step, and 85 a lever pivoted on the structure to which said arm is pivoted, of a stop member secured on said step structure adapted to receive the point of pivotal connection of the said arm and lever against it when the step 90 is lowered for sustaining the latter positively in its position for use.

2. In a device of the nature described, the combination with a step structure including an auxiliary step suspended therefrom adapted to fold beneath it, an arm rigidly secured to said auxiliary step, and 95 a lever pivoted on the structure to which said arm is pivoted, of a fixed stop substantially at the place of connection of the 100 arm and lever for receiving the latter against it for maintaining the same relatively rigid when the step is in its position for use, an arm attached to the lever for controlling the step, a keeper with which the 105 arm is engageable including means to automatically secure the arm from movement and therethrough secure the said step positively in its said position for use.

3. In a device of the nature described, 110 the combination with a step structure including an auxiliary step suspended therefrom adapted to fold beneath it, an arm rigidly secured to said auxiliary step, and 115 a lever to which said arm is pivoted, of a stop member adapted to receive the place of connection of the said arm and lever against it when the step is lowered for sustaining the same positively in its position for use, an arm attached to the lever, a keeper 120 with which it is engageable including means to automatically and positively lock said arm from movement in the said position for use of said step.

4. In a device of the nature described, 125 the combination with a step structure of a railway coach including an auxiliary step suspended pivotally therefrom adapted to be folded beneath it, an arm rigidly secured thereto, and a lever pivoted on the struc- 130

- ture connected to the arm, of a stop to receive one of the last named parts against it forming a lock to support the step in its position for use, latching parts fixed with respect to the auxiliary step and the said step structure adapted to automatically engage when the step is raised to its folded position for sustaining said step in that position.
- 10 5. In a device of the nature described, the combination with a step structure of a railway coach including an auxiliary step suspended pivotally therefrom adapted to be folded beneath the same, an arm rigidly secured thereto and a lever pivoted on the structure connected to the arm, of latching parts on the structure to automatically engage and secure the said auxiliary step in its position for use, and other parts on the structure adapted to automatically engage for holding the step in its raised or folded position.
- 15 6. In a device of the nature described, the combination with a step structure of a railway coach including an auxiliary step suspended pivotally therefrom adapted to be folded beneath the same, an arm rigidly
- 20
- 25
- secured thereto and a lever pivoted on the structure connected to the arm, of parts on the step structure and the auxiliary step mechanism adapted to automatically engage when the said step is raised for holding it in that position.
- 30
7. In a device of the nature described, the combination with a step structure of a railway coach including an auxiliary step suspended pivotally therefrom adapted to be folded beneath the same, an arm rigidly secured thereto and a lever pivoted on the structure connected to the arm, of parts on the step structure and the auxiliary step mechanism adapted to automatically engage when the said step is raised for holding it in that position, and means on the said mechanism to engage and release one of the parts in lowering the step for use.
